UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

MINING-MACHINE TRUCK.

1,141,943.

Specification of Letters Patent.

Patented June 8, 1915.

Application filed September 14, 1912. Serial No. 720,366.

To all whom it may concern:

Be it known that I, CHARLES E. DAVIS, a citizen of the United States, residing at Chicago, in the county of Cook and State of Illinois, have invented a certain new and useful Improvement in Mining-Machine Trucks, of which the following is a specification.

This invention relates to improvements in mining machine trucks and has for its object to provide a new and improved device of this description.

The present invention may be used for transporting mining machines of any desired description from point to point, but is particularly adapted to be used in mines where the distance between the floor and the roof is comparatively small.

The invention is illustrated in the accompanying drawings, wherein—

Figure 1 is a plan view of one form of truck embodying the invention; Fig. 2 is a side elevation of the device shown in Fig. 1; Fig. 3 is an enlarged sectional view taken on line 3—3 of Fig. 1; Fig. 4 is an enlarged sectional view taken on line 4—4 of Fig. 1.

Like numerals refer to like parts throughout the several figures.

As shown in the drawing, the truck is provided with a frame 1 mounted upon the wheels 2 and 3, said frame being stationary with relation to said wheels. The wheels 2 are the rear wheels and the wheels 3 are the front wheels. A movable frame 4 is provided which movable frame constitutes the bed of the truck and receives the mining machine. This movable frame is arranged so that it revolves or rocks about the axle line of the rear pair of wheels and is also capable of moving lengthwise with relation to the truck. As herein illustrated, the movable frame 4 is provided with a slot 5 into which is received the rear axle 6 of the rear wheels. This slot may be formed in any desired manner as by means of the loop 7. When the movable frame 4 is in position to load the machine as shown in Fig. 2, for example, it is inclined, the lower end resting on the floor. The front end of the movable frame is lifted as the frame is moved along the stationary frame by means of the inclined face 8 attached to the movable frame, said inclined face engaging an opposed face connected with the stationary frame. As here-

in shown, the opposed face on the stationary face consists of a roller 9. This roller is connected with the stationary face below the front axle, as shown in Fig. 4. In the particular construction shown, the front wheels 3 are mounted upon the studs 3^a which pass through the side pieces of the stationary frame 1 (see Fig. 3). The rollers 9 are mounted upon pins connected with the projections on said frame, the parts being arranged so that the movable frame 4 at the front end can pass below the axles of the wheels 3. By using a roller, the friction due to the movement is decreased. I prefer to have two rollers 9 and two inclined faces 8, one at each side of the frame, as shown in Fig. 3. Some means is preferably provided for preventing the longitudinal movement of the movable frame while the mining machine is being moved thereon. I prefer to make this means automatic so that when the mining machine reaches a predetermined position on the movable frame, the holding device automatically releases, so that the frame and mining machine together may then be moved until the front end of the movable frame is lifted a desired amount. As shown in the drawing, this result is accomplished by means of a stop 10 which is movably mounted on the rear axle 6, and which is provided with a weighted end 11 which normally holds it in its operative position in the path of the cooperating engaging part 11 on the movable frame. This stop is provided with a beveled part 12 which projects above the bottom of the movable frame into the path of the mining machine and which is engaged by the mining machine as it is moved on the movable frame thereby being moved down so as to move the locking part 10 out of the path of the cooperating part 11, thus leaving the movable frame free to move along the stationary frame. The movable frame is also provided with the engaging parts 13 which engage the frame of the mining machine as shown in Fig. 2 so as to fasten the machine to the movable frame. Some means is provided for limiting the movement of the movable frame so that the rollers 9 will be in engagement with the beveled faces 8 when the front end of the movable frame is lifted a desired amount so that when the movable frame is released, it will automatically move

to its unloading position due to the inclined face or faces 8. As herein shown, this limiting device is the part 14.

In the use of the device, the movable frame is moved to the position shown in Figs. 1 and 2 where the front end engages the floor of the mine. The movable frame is then locked against longitudinal movement. The front end of the inclined movable frame is then placed under the mining machine and the mining machine moved therealong until it engages the part 13 so as to move the stop 10 to its inoperative position. The further movement of the mining machine then carries the movable frame 4 along with it, the front end of the movable frame being gradually lifted by the inclined faces 8. The part may be held in this position by means of a holding device 16. When it is desired to unload the mining machine, the holding device 16 is released whereupon the frame and mining machine automatically moves to the position shown in Fig. 2, the inclined faces 8 moving along the rollers 9.

It will be seen that in this device, the movable frame rocks or rotates about the axle line of the rear pair of wheels that is, the axle line of the pair of wheels farthest from the loading end. This construction keeps the top of the mining machine low while being loaded and makes it so that the uppermost point only moves through a small arc while the device is being loaded. It will be seen that if the frame moves about the front axle, the mining machine would have to run up higher in the air and could not then be loaded in places where there is a limited space between the floor and the roof.

I claim—

- 40 1. A mining machine truck comprising a stationary frame mounted on four wheels and a movable frame constituting the bed of the truck and capable of revolving about the axle line of the pair of wheels farthest from the loading end of the frame.
- 45 2. A mining machine truck comprising a stationary frame mounted on four wheels and a movable frame capable of revolving about the axle line of the pair of wheels farthest from the loading end of the frame and also capable of moving lengthwise with the truck.
- 50 3. A mining machine truck comprising a stationary frame mounted on four wheels and a movable frame capable of revolving about the axle line of the pair of wheels farthest from the loading end of the frame and also capable of moving lengthwise with the truck, a latch to prevent the said longitudinal motion occurring before the mining machine reaches a predetermined position on the truck.

4. A mining machine truck comprising a stationary frame mounted on four wheels and a movable frame capable of revolving about the axle line of the pair of wheels farthest from the loading end of the frame and also capable of moving lengthwise with the truck, and means for causing the movable frame to move forward when unloading the machine.

5. A mining machine truck comprising a stationary frame mounted on four wheels and a movable frame capable of revolving about the axle line of the pair of wheels farthest from the loading end of the frame and also capable of moving lengthwise with the truck, and means for propelling the movable frame to move backward with the machine under predetermined conditions.

6. A mining machine truck comprising a stationary frame mounted on four wheels and a movable frame capable of revolving about the axle line of the pair of wheels farthest from the loading end of the frame and also capable of moving lengthwise with the truck, and means for elevating the forward end of the movable frame as it moves backward on the truck.

7. A mining machine truck comprising a stationary frame mounted on four wheels and a movable frame capable of revolving about the axle line of the pair of wheels farthest from the loading end of the frame and also capable of moving lengthwise with the truck, and means for preventing excessive longitudinal motion of the movable frame.

8. The combination with a stationary frame mounted on wheels of a longitudinal movable frame adapted to be moved to an inclined position, an inclined face on the movable frame and a coöperating face on the stationary frame, said latter face located below the axis of rotation of the front wheels whereby when the movable frame is moved longitudinally, the front end of the movable frame is lifted.

9. A mining machine truck comprising a stationary frame mounted on four wheels and a movable frame constituting the bed of the truck, said movable frame capable of revolving about the axle line of the pair of wheels farthest from the loading end of the frame and means for simultaneously supporting the other end of the frame upon the remaining wheels, while this movement is taking place.

Signed at Chicago, Illinois, this 10th day of September 1912.

CHARLES E. DAVIS.
